CIRCUIT CONTROL DEVICE

Clarence W. Moore, Roslyn, Pa., assignor, by
mesne assignments, to United Specialties Com-
pany, Detroit, Mich., a corporation of Dela-
ware

Application May 28, 1934, Serial No. 727,976

12 Claims.

(Cl. 200—44)

This invention relates to circuit control devices and involves various improvements in combined switch and lock structures. As illustrated herein, these improvements are embodied in a combined switch and lock of a type employed primarily for controlling the electrical circuits of automobile ignition and starting devices, but it is to be understood that the invention is equally useful for controlling circuits other than those specifically disclosed.

One of the principal objects of the invention is the provision, in a circuit control switch having manually operated means for moving a contactor element into a plurality of positions, of means for automatically returning the contactor element to a predetermined position when moved therebeyond by the manually operated means. In the preferred form of the device, this purpose is accomplished by the use of stationary contact elements and a rotary contactor having manually operated means for moving it into cooperative relation with the various stationary contact elements, the manually operated means actuating the rotary contactor through a rotary lock cylinder having a coiled spring associated therewith in such a manner as to be placed under sufficient tension to return the rotary contactor to one of its circuit controlling positions when it is moved therebeyond by the manually operated means.

The construction and arrangement of the stationary contacts and the movable contactor are such that, when the movable contactor is rotated by the manually operated means to the limit of its movement in one direction, both the ignition and starter circuits of the automobile are closed, and as soon as the manually operated means is released the movable contactor is returned to a position with respect to the stationary contact elements wherein the starter circuit is broken while the ignition circuit remains closed, the movable contactor remaining in the position for normal operation of the automobile engine until it is moved therefrom by the manually operated means.

A further object of the invention is the provision of means for rendering the automatic means ineffective when the movable contactor is in a predetermined cooperative relation with respect to the stationary contact elements. This object is accomplished by so constructing the stationary contact elements and the movable contactor that there is no resistance to the operation of the automatic means when the movable contactor is in a position to energize the

starter circuit, and by so constructing the stationary contact elements and the movable contactor as to prevent the automatic means from returning the movable contactor beyond the position for normal operation of the engine.

A still further object of the invention is the provision of an improved terminal block for the stationary contact elements. In terminal blocks of this general character it is the usual practice to embed the stationary contact elements in a block of insulating material, preferably of a kind which may be readily molded. Phenol-resin compositions are particularly well adapted for use in such terminal blocks and are commonly used for that purpose. It has been the practice heretofore in making such blocks to mold the contact elements or terminal posts in the block, or to insert these elements in suitable openings provided in the blocks when they are molded. In either case, it has been necessary to grind off the ends of the terminal posts which form the contact elements in order to bring the operating faces of the contact elements into positions flush with the face of the block and polish them to such an extent that they would not interfere with the proper operation of the movable contactor.

Under the practice heretofore followed, it has been difficult to grind off the surfaces of the contact elements without destroying the polished surface inherent in the molded phenol-resin block. With a terminal block constructed in accordance with the present invention, the operating surfaces of the stationary contact elements may be ground and polished to such extent as is necessary without interfering in any way with the polished surface of the insulating material.

A still further object of the invention is the provision of improved means for retaining the various parts of the switch structure in assembled relation. This object is accomplished by enclosing the switch elements within a suitable housing, with certain elements seated upon parts of the housing when the elements are in assembled relation, and by retaining them in assembled relation by means of a cover plate secured in the open end of the housing.

Other objects and advantages of the improved structure will be apparent from the following description, taken with the accompanying drawings wherein:

Fig. 1 is a longitudinal sectional view through the device supported in position in the rear of the instrument panel of an automobile;

Fig. 12 is a reduced elevational view of the face plate for the terminal block;

Fig. 13 is a diagrammatic view showing the movable contactor in a position wherein the battery circuit is open and the starter, ignition and gasoline gauge circuits are grounded;

Fig. 14 is a diagrammatic view showing the movable contactor in a position to close the battery, ignition and gasoline gauge circuits; and

Fig. 15 is a diagrammatic view showing the movable contactor in a position to close the battery, starter, ignition and gasoline gauge circuits.

The combined lock and switch elements of the device illustrated herein are enclosed within a housing 10 comprising a cylindrical front portion 11 and an enlarged cylindrical rear portion 12. The forward end of the front portion 11 abuts against the edge of an opening 13 in a reinforcing sub-panel 14, this opening alining with a similar opening 15 in the instrument panel 16 of the automobile. The housing 10 is secured in this position by means of a pair of bolts 17 engaging with a pair of oppositely extending arms 18 integral with the housing, the heads of the bolts preferably being countersunk in the sub-panel 14 and welded thereto.

A lock structure, preferably of the type including a rotary cylinder 19, is encased within the front portion 11 of the housing so that its forward end extends slightly in advance of the front end of the body of the housing as shown in Fig. 1. The front end of lock cylinder 19 is provided with a suitable opening 20 for receiving a key 21 by means of which the lock is actuated and the movable element of the switch structure is moved into its various circuit controlling positions. The lock cylinder 19 may be of any well known construction and is preferably of the type in which a plurality of spring pressed plungers 22, extending transversely of the cylinder, engage with a longitudinal groove in the housing in order to retain the device in locked position, unlocking thereof being accomplished by the insertion of the key 21. The cylinder 19 is retained within the housing by the engagement of an arcuate, spring pressed retainer plate 23 with an annular shoulder 24 on the inside of the housing.

Inasmuch as the housing 10 is preferably formed by a casting operation, a structure is utilized for finishing the front end thereof easily and economically without necessitating the appli-

cation of the usual finishing processes to the body of the housing. As shown herein, the marginal edge of the front end of the housing is provided with a forwardly extending flange 25 and an annular groove 26 located within this flange. A finished ferrule 27 has its inner end seated within the annular groove 26 and its outer end extending into the alined openings 13 and 15 in the sub-panel and the instrument panel. A finished washer 28 is provided with a central opening 29 to receive the front end of the lock cylinder 19 and is supported upon the front end of the body portion of the housing and retained in position thereon by means of a shoulder 30 on the inside of the ferrule 27.

The ferrule 27 is provided with an arcuate slot 31 alining with a cutaway portion 32 in the flange 25 in order that the front end of the lock cylinder 19 may be provided with indirect illumination from the light 33 supported in the rear of the instrument panel. The ferrule 27 may be secured against rotary movement by providing the washer 28 with oppositely arranged shoulders 34 extending through the slot 31 and engaging with the ends thereof, and by providing the washer 28 with a radial lug 35 extending through the slot 31 and having its angularly bent end engaging within a notch 36 in the flange 25. The ferrule 27 may be retained in position on the housing by indenting or staking the flange 25 at intervals in such a manner that the staked portions 37 engage with a circumferential shoulder 38 on the outside of the ferrule.

Mounted within an annular recess 39 between a reduced portion on the rear end of the cylinder 19 and a cap member 40 non-rotatable with respect to the cylinder and secured thereon by means of a screw 41 is a coiled spring 42 one end 45 of which is bent outwardly and extends into an opening 46 in the cap member. The opposite end 43 of the coiled spring 42 is bent outwardly and extends through an arcuate slot 44 in the forward end of the cap member 40 and into a position for engagement with a stop pin 47 on the inside of the housing to thereby tension the spring when the key 21 is turned to rotate the movable switch element beyond a predetermined position.

The inner end of the cap member 40 is provided with a pair of spaced lugs 48 for engagement within a transversely extending recess 49 of a cylindrical block 50 of insulating material upon which the movable contactor 51 is mounted. A positioning lug 52 may also be provided on cap member 40 for engagement within a corresponding recess in block 50 to locate the contactor 51 when the parts are assembled in the housing.

The contactor 51 is substantially triangular in shape and is provided with three spaced contact elements 53 pressed outwardly from one side thereof, and an outwardly pressed central boss 54 on the opposite side for engagement within one end of a coiled spring 55 the opposite end of which is seated within a recess 56 in the adjacent face of the block 50. The contactor 51 is provided with a pair of oppositely arranged arms 57 which extend into diametrically arranged grooves 58 in the block 50, with the free ends thereof bent inwardly for engagement with abutments 59 to retain the contactor 51 in position with respect to the block before the parts are assembled in the housing. When the block 50, with the contactor 51 secured thereto, is assembled in cooperative relation to the cap mem-

ber 40, the edge of the block seats upon a shoulder 60 formed on the inside of the housing.

The movable contact elements 53 cooperate with a plurality of stationary contact elements 5 supported by the terminal block 61. While the number and arrangement of the stationary contact elements may be varied as may be required by the circuits to be controlled, the structure shown herein is adapted for use in controlling 10 starter, ignition and gasoline gauge circuits and for grounding these circuits when the movable contactor is rotated into a position to break the battery circuit.

The contact element B constitutes one end of 15 a terminal post 62 extending through the terminal block 61 and having a binding screw 63 threaded in the opposite end thereof with which connection to the battery is made. The contact element B is secured within an opening in 20 one end of a bridging contact strip 64 the opposite end of which is secured to one end of an anchor post 65 the opposite end of which is secured within the base 66 of the terminal block as shown in Fig. 8.

25 The contact element T constitutes one end of a terminal post 67 which extends through the terminal block and has a binding screw 68 threaded in the opposite end thereof to which connection with the gasoline gauge is made. 30 The contact element T is likewise secured in one end of a bridging contact strip 69 the opposite end of which has secured therein an anchor post 70 having its inner end secured within the base 66 as shown in Fig. 9. The contact element T 35 also has secured thereto beneath the bridging strip 69 one end of a bridging element 71 positioned within a central opening in the base 66 and having the ignition cable 72 connected thereto. The opposite end of the bridging element 40 71 is secured to the inner end of a stub post 73 the outer end of which forms a contact element I.

The contact element S constitutes one end of a terminal post 74 which extends through the 45 terminal block and is threaded at its opposite end to receive a binding screw 75 to which the wiring for the starter is connected.

As shown in Fig. 10, the stationary contact element G is in the form of a stub post having 50 its inner end extending into the base 66 and engaging with a grounding strap 76 the outer end of which contacts with the wall of the housing when the terminal block is assembled therein.

The base 66 of the terminal block is preferably molded from a phenol-resin composition. While it may be molded with the various terminal posts and anchor posts in position therein, it is preferably molded with suitable openings 55 therein to receive the terminal posts and anchor posts. As disclosed herein the terminal posts 62, 67 and 74 are provided with annular milled or otherwise roughened portions 77 for tight frictional engagement with the walls of the respective openings in the base when the posts are pressed into position therein. These posts may also be provided with non-circular portions 78 for engagement within correspondingly shaped recesses in the base to prevent rotation of the posts when assembled therein. The 60 various terminal posts and anchor posts are also provided with annular flanges 79 which seat within corresponding recesses in the face of the base 66, the outer faces of these flanges being positioned in the same plane slightly outwardly 65 of the face of the base to form a seat for the

wear-resistant face plate 80. The outer face of the flange on the terminal post 67 is positioned inwardly of the plane of the outer faces of the other flanges 79 by reason of the positioning of one end of the bridging member 71 thereon, and in this case the outer face of the end of the bridging member 71 is in the plane of the other flanges. 5

The face plate 80 is formed from wear-resistant insulating material, preferably a laminated, phenol-resin composition. In making the terminal block 61 the various terminal posts and anchor posts, with the bridging strips secured thereto, are pressed into their respective openings in the base 66 so that the outer faces of the flanges 79 formed thereon are in the same plane, it being understood that the flange 79 on the terminal post 67 is located as hereinbefore described. The various stationary contact elements, together with the bridging contact strips 64 and 69, are then ground off until these elements are in the same plane. The face plate 80, formed with suitable openings therein to receive the various contact elements and the bridging contact strips as shown in Fig. 12, is then seated on the annular flanges on the terminal posts and the anchor posts, the thickness of the plate being such that the contact elements and bridging strips will be flush with the outer face thereof. By making the terminal block in this manner 30 the necessity of grinding off the contact elements after the parts are assembled is avoided, and full advantage may be taken of the polished, wear-resisting face of the laminated face plate as it comes from the mold. 35

When the assembled parts of the terminal block 61 are inserted in the cylindrical portion 12 of the housing, the edge of the face plate 80 seats upon a shoulder 81 on the inside of the housing, and the terminal block together with the movable contactor, is retained in position by means of a closure plate 82. This closure plate is provided with suitable openings to receive the insulated bosses through which the terminal posts 62, 67 and 74 extend, and it preferably has a ferrule 83 secured thereto within which one end of the armor 84 for the ignition cable 72 is secured. The closure plate is retained in position by turning the edge of the open end of the enlarged portion 12 of the housing inwardly thereover. The terminal block is located in the housing and held against rotation therein by the engagement of a lug 85 on the housing within a slot 86 in the base 66 as shown in Figs. 6 and 7, and a corresponding notch 87 is provided in the edge of the face plate 80 for engagement with the lug 85 when the parts are assembled. 50

Referring to Figs. 13, 14 and 15 of the drawings it will be seen that when the contactor 51 is rotated to the limit of its movement in a clockwise direction by the key 26, as shown in Fig. 15, whereby the starter and ignition circuits are connected to the battery circuit, the three contact elements 53 are in engagement with stationary 65 contact elements B, T and S. These stationary contact elements are provided with smooth surfaces in order not to interfere with the action of coiled spring 42 in returning the contactor to the position of normal engine operation as illustrated in Fig. 14. When in the latter position the contact elements 53 are in engagement with the cupped ends of anchor posts 65 and 70 and cupped contact I of stub post 73. The cupped formation of stationary contact element I and 75

the outer ends of anchor posts 65 and 70 operates to discontinue the return movement of contactor 51 from the starter position under the action of spring 42 so that when the key is inserted in the lock to unlock the device and is then turned in a clockwise direction to rotate the contactor 51, spring 42 will be tensioned as the contactor moves from the position shown in Fig. 13 to the position shown in Fig. 15, and upon the release 10 of the key the contactor is rotated by spring 42 in a counter-clockwise direction away from the starter position and is positively stopped in the position of normal engine operation, from which it may be rotated in either direction by means 15 of a key.

When the contactor 51 is in the position shown in Fig. 13, wherein the battery circuit is broken and the starter, ignition and gasoline gauge circuits are grounded, two of the contact elements 20 53 are in engagement with smooth stationary contact elements T and S and the other element 53 is in engagement with the cupped end of grounding contact G. In this case a single cupped stationary contact is sufficient to indicate 25 to the operator that the contactor is in a position wherein the key may be withdrawn to lock the device.

While certain forms and arrangements of the elements employed in the invention are disclosed 30 herein, it will be understood that these are illustrative and that various changes may be made therein without departing from the invention as defined by the appended claims.

What is desired to secure by Letters Patent is:

1. In a combined switch and lock structure, a housing, a rotary lock cylinder mounted therein, a rotary contactor member mounted therein for movement into a plurality of circuit controlling positions, means interengaging said cylinder and 40 said member to transmit rotary motion from said cylinder to said member, manually operated means for actuating said cylinder to move said member into its various circuit controlling positions, a spring coiled around said cylinder and 45 having one end connected thereto for movement therewith and the opposite end connected thereto for limited relative movement with respect thereto and a stop on said housing for engagement with the latter end of said spring to tension said spring and thereby return said member to one of said positions when moved therebeyond by said manually operated means.

2. In a circuit control device, a terminal block comprising a base of insulating material, a plurality of spaced terminal posts secured in said base and having the ends thereof protruding from one face of the base and positioned in the same plane to provide stationary contact elements, a shoulder on each of said posts positioned 55 slightly outwardly of the face of said base, said shoulders being uniformly spaced from the protruding ends of said posts, a sheet of insulating material having openings therein to receive said contact elements and supported upon said shoulders with its exposed face flush with the protruding ends of said posts, and means to retain said sheet in position.

3. In a circuit control device, a terminal block comprising a molded base of insulating material 70 having a plurality of spaced openings extending therethrough and provided with enlargements in one face thereof, terminal posts secured in said openings with the ends thereof positioned in the same plane outside of said enlargements to provide stationary contact elements, flanges on said

posts positioned in said enlargements with the outer faces thereof located in a plane between the adjacent face of said base and the plane of said contact elements, and a sheet of wear-resistant insulating material having openings 5 therein to receive said contact elements and supported upon said flanges with its exposed face flush with said contact elements.

4. In a circuit control device, a plurality of spaced terminal posts having the adjacent ends 10 thereof in the same plane to provide stationary contact elements, a shoulder on each of said posts, said shoulders being uniformly spaced from said ends, an insulating support for said posts, and a face plate of molded, wear-resistant 15 insulating material removably seated on said shoulders and having openings therein to receive said contact elements, with the outer mold- 20 ed surface of said plate flush with said ends.

5. In a circuit control device, a base member 20 of insulating material, a plurality of spaced terminal posts supported in said base with the adjacent ends thereof terminating in the same plane outwardly of one face of said base to provide stationary contact elements, an outwardly 25 projecting shoulder on each of said posts, said shoulders being in a plane positioned outwardly of the adjacent face of said base member, and a face plate of wear-resistant insulating material 30 removably seated on said shoulders and having the exposed face thereof in the plane of said ends.

6. In a circuit control device, a terminal block including a base of molded insulating material, a plurality of spaced terminal posts secured in 35 said base with the ends projecting from one face thereof to provide stationary contact elements, a shoulder on each of said posts, said shoulders being uniformly spaced from said ends, and a face plate of wear-resistant insulating material 40 seated on said shoulders and having its exposed, molded face in the plane of said ends, a housing enclosing said block, and means on said housing for retaining said base and said plate in assembled relation.

7. In a circuit control device, a terminal block comprising a base of insulating material, a plurality of spaced terminal posts secured in said base with the ends projecting from one face thereof to provide stationary contact elements, 50 a shoulder on each of said posts, said shoulders being uniformly spaced from said ends, and a face plate of wear-resistant insulating material removably seated on said shoulders with its exposed face in the plane of said ends, a movable contactor element cooperating with said stationary contact elements, a housing enclosing said block and said contactor element, and means on said housing for retaining said base, said plate and said contactor element in assembled relation.

8. In a circuit control device, a housing having two spaced shoulders on the interior thereof, a rotary contactor member supported on one of said shoulders, a terminal block of insulating material supported on the other of said shoulders and having a plurality of stationary contact elements mounted thereon in cooperative relation to said rotary contactor member, spring means for urging said contactor into engagement with said block, and means in said housing for retaining said terminal block and said rotary contactor member in assembled relation.

9. In a combined switch and lock structure, a rotary locking member having a reduced portion on one end thereof, a rotary contactor 75

- member movable into a plurality of circuit controlling positions, means interconnecting said locking member and said contactor member to transmit rotary motion from said locking member to said contactor member, manually operated means for actuating said locking member to move said contactor member into each of its circuit controlling positions, a spring coiled around the reduced portion of said locking member and having one end connected to said locking member for movement therewith and the opposite end connected to said locking member by a lost motion connection, and a stop for engagement with the latter end of said spring to tension the same and thereby return said contactor member to one of its positions when moved therebeyond by said manually operated means.
10. In a combined switch and lock structure, a rotary locking member, a rotary contactor member movable into a plurality of circuit controlling positions, means interconnecting said locking member and said contactor member to transmit rotary motion from said locking member to said contactor member, manually operated means for actuating said locking member to move said contactor member into each of its circuit controlling positions, a coiled spring having one end arranged for movement with said locking member and the opposite end arranged for limited relative movement with respect to said locking member, and a stop for engagement with the latter end of said spring to tension the same and thereby return said con-

tactor member to one of its positions when moved therebeyond by said manually operated means.

11. In a circuit control device, a contact supporting member comprising a base of insulating material, a plurality of spaced terminal posts secured in said base, with the ends protruding therefrom to provide contact elements in the same plane, and a sheet of molded, wear-resistant insulating material having openings therethrough to receive the protruding ends of said posts and having its outer molded and polished surface flush with said contact elements.

12. In a combined switch and lock structure, a housing member, a rotary locking member, a rotary contactor member movable into a plurality of circuit controlling positions, means interconnecting said locking member and said contactor member to transmit rotary motion from said locking member to said contactor member, manually operated means for actuating said locking member to move said contactor member into each of its circuit controlling positions, a spring operatively connected between said locking member and said housing member, one end of said spring being fixed with respect to one of said members and the opposite end of said spring having a lost motion connection with the other of said members, and a stop for engagement with the latter end of said spring to tension the same and thereby return said contactor member to one of its positions when moved therebeyond by said manually operated means.

CLARENCE W. MOORE.
